UNITED STATES PATENT OFFICE.

JOHN KEARWILLE, JR., OF CENTREVILLE, IOWA.

HARNESS-LOOP.

SPECIFICATION forming part of Letters Patent No. 289,269, dated November 27, 1883.

Application filed August 7, 1883. (No model.)

To all whom it may concern:

Be it known that I, JOHN KEARWILLE, Jr., a citizen of the United States, residing at Centreville, in the county of Appanoose and State of Iowa, have invented certain new and useful Improvements in Harness, of which the following is a specification, reference being had thereto in the accompanying drawings.

My invention has relation to harness for horses and more particularly to guides for the traces; and its object is to provide a guide or loop secured to and made adjustable upon the pad-skirt, so as to support the trace between the collar and the single-tree; and to that end the novelty consists in the construction of said guide and its combination with the trace and pad-skirt, as will be hereinafter more fully described.

In the accompanying drawings similar letters of reference indicate like parts of the invention.

Figure 1 is a perspective elevation of a horse with my improved harness in position. Fig. 2 is a perspective view of a portion of the belly-band and pad-skirt with the trace-guide. Fig. 3 is a view of the guide detached from the harness; and Fig. 4 is a longitudinal section through the belly-band, pad-skirt, and guide.

A is the pad-skirt, and B the belly-band, which passes through a keeper, C, and thence around underneath the body of the horse, and is fastened in the usual manner.

D is the metallic trace-guide, and it consists of a plate, E, having straps *e e*, which encompass the band B so as to slide freely upon it. 35 *e'* is a stud secured to the plate E, so as to engage the holes *e*² on the band B, and thereby secure the trace-guide at any position upon said band.

F is a loop or strap through which the trace 40 G passes, and is of a size to allow the trace a free motion longitudinally, but at the same time prevent all unnecessary play or up-and-down motion. By moving the guide up or down and securing it in position by the stud 45 *e'* in the holes *e*², it may be readily adjusted to suit the requirements of horses or mules of different size.

Having thus described my invention, what I claim as new and useful, and desire to secure 50 by Letters Patent of the United States, is—

As an improved article of manufacture, the metallic trace loop or guide consisting of the base-plate E, having strap-loops *e e* and stud *e'*, intermediate said loops on the inside, and at a right angle to the loops *e e*, constructed substantially as and for the purpose set forth.

In testimony whereof I affix my signature in presence of two witnesses.

JOHN KEARWILLE, JR.
